UNITED STATES PATENT OFFICE.

HARRY G. JENNISON, OF TOLEDO, OHIO.

WOOD PAVEMENT.

1,302,560.

Specification of Letters Patent.

Patented May 6, 1919.

Application filed October 23, 1914. Serial No. 368,177.

To all whom it may concern:

Be it known that I, HARRY G. JENNISON, a citizen of the United States, residing at Toledo, Lucas county, Ohio, have invented 5 new and useful Wood Pavements, of which the following is a specification.

This invention relates to wood treatment, or treatment of materials having expansion and shrinkage, as well as spacing provision 10 between elements of material.

This invention has utility in the preparation of timber and the grouping of elements or blocks of material, having especial value when the above features are combined in the 15 production of deformation minimized wood blocks for incorporation into pavements or floors.

Referring to the drawings:

Figure 1 is a plan view of a paving block 20 shrunk;

Fig. 2 is a plan view of an unshrunk paving block embodying features of the invention;

Fig. 3 is a fragmentary plan view of a 25 pavement embodying features of the invention after shrinking has occurred;

Fig. 5 is a perspective view of a paving block of Fig. 2; and

Fig. 5 is a perspective view of a paving 30 block with expansion take-up as well as shrinkage provision.

The seasoned or dry block 1, impregnated say with a hydrocarbon, and installed in a floor protected from moisture will in its 35 aging shrink as much as 7%, enlarging to an objectionable extent the intermediate filling space between the blocks and exposing the corners to extra wear and fracture, thereby reducing the life of the pavement as 40 a smooth floor.

The paving block of Figs. 2, 4, has the wear face 2 parallel to the face 3, each across the grain of the timber of the block and connected by the block side walls 4 into 45 which extend the openings 5 inwardly from the wall and the full length of the side 4, as well as part way across the faces 3, 2, to intercept the larger or longer arc age rings 6. These blocks having the wear faces 2 upon such dry use are subject to shrinkage 50 action, but the pulling together or diameter reducing action of the longer arc age rings 6 is distributed and dissipated by each opening 5, and the shrunk block has its wear face 7 with the openings 8 each taking a portion of the shrinkage. With two open-

ings intercepting the longer arc age rings, the overall shrinkage in length of the block of Fig. 3 is approximately one third the shrinkage of the unopened block of Fig. 1. 60

Instead of merely interrupting the continuity of the longer arc rings, in the block of Fig. 5, this block 9 has the openings 10 initially configured to permit expansion of these larger arc age rings. These blocks are 65 designed to stand weathering and within themselves dissipate nearly all the dimensional changes due thereto, thereby producing most simply a dependable wood block pavement. 70

The growth rings appear to act as units under moisture variations. The shorter rings which run out the side walls of the block, having but a fractional extent of the block involved in their change, do not prove 75 such disturbing factors as those rings approximating the longer transverse block dimensions. Creating openings by rupturing these major or longer arc age rings in the blocks does not interfere with the deformation of the rings, but the added number of places from which to pull, or into which to push, dissipates these changes to such an extent within the block that the excess becomes such a negligible quantity as 80 not to disturb regular laying. These conditions arise with impregnated, creosoted and natural wood blocks, and the ring opening treatment effectively minimizes external dimension deformation by dissipating inside 85 thereof. 90

What is claimed and it is desired to secure by Letters Patent is:

1. A pavement comprising rigid grain-up wood paving blocks providing arcs of 95 age rings in cross sections parallel to the pavement face of the block, said blocks being independently removable from the face of the pavement, and said blocks having within the contour of the blocks, interception means for the longer arc age rings, said interception means extending through the pavement from the pavement face to break up longer arc rings into a plurality of 100 arc sections whereby expansion and contraction disturbances may be dissipated within the region as laid of the respective blocks of the pavement. 105

2. In a pavement comprising oblong grain-up wood blocks disposed in rows, the 110 joints of the blocks of one row of the long way of the blocks being staggered with /

joints of the blocks of the adjacent row, the means of taking care of block contraction embodying having said blocks individually rigid with the shorter arc age rings 5 arching from one of the long sides of the block toward the opposite long side of the block, there being a notch in this latter side of the block which notch extends downward clear through the block from the pavement 10 face to break up longer arc age rings of the block, and thereby leave the block from the

root of the notch toward the shorter arc age ring side as a rigid portion between the ends of the block holding the block lengthwise for contraction of the block to open the 15 notch.

In testimony whereof I hereunto set my hand in the presence of two witnesses.

HARRY G. JENNISON.
